CLAIM

The ornamental design for a shoe, as shown and described.

DESCRIPTION

FIG. 1 is a bottom perspective view of a shoe showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged view of the area 8 shown in dot-dot-dash lines in FIG. 4.

The dot-dash broken lines in the figures show boundaries forming no part of the claimed design and the lightened area(s) outside the dot-dash broken lines show portions of the shoe that form no part of the claimed design.

The dot-dot-dash broken lines in the figures show area of enlargement and the dot-dot-dash broken lines form no part of the claimed design.

1 Claim, 8 Drawing Sheets
